GARTER BELT

Harry W. Froehlich, Pacific Palisades, Calif., assignor to Charmfit of Hollywood, Inc., Los Angeles, Calif., a corporation of California

Filed Oct. 28, 1963, Ser. No. 77,160

Term of patent 14 years

(Cl. D20—2)

FIG. 1 is a front elevational view of a garter belt showing my new design; and

FIG. 2 is a rear elevational view of the same.

I claim:

The ornamental design for a garter belt, substantially as shown.
